(57) **CLAIM**

The ornamental design for a tooth brush ionizer, as shown and described.

DESCRIPTION

FIG. 1 is a front perspective view of a tooth brush ionizer, showing my new design;

FIG. 2 is a rear perspective view thereof;

FIG. 3 is a front elevation view thereof;

FIG. 4 is a rear elevation view thereof;

FIG. 5 is a side elevation view of one side thereof;

FIG. 6 is a side elevation view of the other side thereof;

FIG. 7 is a top plan view thereof; and,

FIG. 8 is a bottom plan view thereof.

The broken-line showing of a portion of a tooth brush in the views is for illustrative purposes only and forms no part of the claimed design.
